UNITED STATES PATENT OFFICE.

JOSEPH E. STEPHENSON, OF YOUNGSTOWN, OHIO.

WASHBOWL.

1,020,324.

Specification of Letters Patent. Patented Mar. 12, 1912.

Application filed March 1, 1910. Serial No. 546,691.

To all whom it may concern:

Be it known that I, JOSEPH E. STEPHENSON, a citizen of the United States of America, residing at Youngstown, in the county 5 of Mahoning and State of Ohio, have invented new and useful Improvements in Washbowls, of which the following is a specification.

This invention relates to wash-bowls, and 10 has for an object to provide a device of this character including a main bowl-forming portion, a surrounding annular wall and a top or ledge portion which connects the said annular wall with the said bowl-forming 15 portion, the controlling means for the valve being extended through the said annular wall in positions where they may be conveniently grasped and manipulated by the operator to permit the entrance of the hot 20 or cold water to the bowl.

A still further object of the invention resides in the construction of the device where- 25 in I am able to provide a basin or bowl having a perfectly smooth or flush top portion enabling the bowl to be always kept in a perfect sanitary condition.

In the drawing, forming a portion of this specification and in which like numerals of reference indicate similar parts in the sev- 30 eral views:—Figure 1 is a top plan view of my improved bowl. Fig. 2 is a vertical longitudinal section therethrough.

My improved bowl may be either made of porcelain, metal or any other desired mate- 35 rial and it consists of a main bowl-forming portion 1, and an angular side portion or wall 2 which entirely surrounds the bowl portion and which is connected thereto by a top or ledge forming portion 3. The bowl- 40 forming portion is provided with hot and cold water inlet nipples 4 and 5 with which are connected the hot and cold water supply pipes 6 and 7. The said pipes 6 and 7 are provided with any well known and approved 45 controlling valves 8 which carry controlling rods 9. These rods are journaled in the por- 50 tions 10 of pockets 11 in the wall-forming portion 2 as shown particularly in Fig. 2 of the drawing. The said controlling rods 9 are provided with suitable actuating knobs or the like 12 which are disposed in the

pockets 11 but positioned therein so that they can be conveniently grasped when it is desired to open or close the valves 8.

The bowl-forming portion 1 is provided 55 at its bottom with a depending discharge nipple 13 which is threaded exteriorly or otherwise suitably formed so that it can be connected with the usual waste pipe (not shown). The said nipple 13 is formed to 60 provide a spider 14 forming a strainer to prevent undesirable particles of foreign matter from being emptied into the waste pipe. It may be mentioned that the strainer-forming spider is positioned adjacent to the ex- 65 treme lower end of the nipple 13 so as to form in said nipple a cavity 15 for the recep- tion of the usual stopper. The bowl-forming portion 1 is formed to provide an over- 70 flow passage 16 which discharges into the duct 17 as illustrated.

The construction of the bowl as herein described and shown is not only simple but incident to the peculiar manner in which I have associated the main bowl-forming portion 1, the wall portion 2 and the top or ledge 3 it will be appreciated that the said top or ledge presents a perfectly smooth or flush surface which effectively obviates the accumulation of filth which usually collects 80 about the faucets of wash-bowls when they are positioned vertically at the top adjacent to the main bowl-forming portion.

It will of course be understood that the 85 valves 8 and their controlling rods 9 can be of any approved well known construction and I do not desire to limit myself to the particular showing of such valves and their controlling rods as are shown herein.

It will of course be understood that I do 90 not desire to limit myself to the use of the invention as a wash-bowl for toilet purposes as it is obvious that it may be used as a re- ceptacle for any obvious purpose such as laundry tubs, bath tubs, foot tubs or the like. 95

I claim:—

In combination, a body of water proof 100 material formed with a bowl, a horizontal table portion connected with the edge of the bowl and a depending flange surrounding the bowl, the wall of the bowl having downwardly inclined openings, water pipes con-

nected with said openings, the depending flange of the body being formed with recesses, stems operating valves in said pipes and extending through said flange and terminating in the recesses thereof, handles secured to the outer ends of said stems and drain openings formed in said bowl.

In testimony whereof I affix my signature in presence of two witnesses.

JOSEPH E. STEPHENSON.
